UNITED STATES PATENT OFFICE.

MOSES APPEL, OF JOHNSTOWN, PENNSYLVANIA.

FURNACE.

Application filed October 28, 1921. Serial No. 511,224.

My invention relates to the construction of furnaces with special reference to means for regulating the gas and air entrance, their flow therein and for providing a larger outlet area to allow the products of combustion to escape from the furnace with ease and without causing undue back pressure, thereby promoting combustion and speedy operation.

10 My invention is particularly applicable to furnaces which are heated with gas, such as producer gas, blast furnace gas, coke oven gas or other distillate gases, and is especially adapted to furnaces of the regenerative or 15 recuperative types, which are provided with gas and air ports in each end.

I provide gas ports and air ports at either end which connect with the flues or channels leading to the slag pockets and thence to the 20 regenerators. The furnace is also provided with the usual regulating valves for gas and air admission and reversing valves to reverse the flow of gases therein, but I have not illustrated these features, as any of the usual 25 appliances and arrangements may be used in connection with my invention.

I provide a gas port or a number of gas ports at each end of the furnace and also an air port or a number of the same at the same 30 end, and these preferably enter the furnace in an upright manner. Above the openings of the ports I provide what I call valve deflectors, the bodies of which may be of metal and water cooled and mounted on a stem which projects upwardly and outwardly 35 from the furnace and is provided with any means for operating the same in order to regulate the size of and openings of the ports, partially or wholly as may be desired.

40 At the entrance my deflector valves may be adjusted so as to control the flow of gases into the furnace and cause them to mix thoroughly in the combustion chamber, and at the outgoing ends the similar deflector valves 45 may be raised higher to give a full and free opening to readily conduct the products of combustion away from the furnace. The inlet gases are thereby easily controlled as may be necessary to produce the best mixture, quantities and combustion, while the 50 outlet is sufficiently open and of large size to permit the products of combustion to pass easily out of the furnace. This allows a large amount of gases to be used in the furnace and causes it to work freely and the products of combustion to be readily dis-

charged without throttling or difficulty as in prior types.

Although my construction is adapted to any type of furnace I have, for ease of illustration and description, shown it herein as applied to an open hearth steel melting furnace.

Having thus given a general description of my invention, I will now, in order to make the matter more clear, refer to the annexed two sheets of drawings, which form part of this specification, and in which like characters refer to like parts.

Figure 1 is a horizontal sectional elevation 70 of the top portion of a furnace illustrating the application of my invention, taken on the line I—I of Figure 2; Figure 2 is a vertical longitudinal sectional elevation of that portion shown in Figure 1, taken on the line II—II of Figure 1; Figure 3 is a vertical transverse sectional elevation taken on the line III—III of Figure 1; Figure 4 is a vertical transverse sectional elevation showing a modified form of my invention taken 80 on the line IV—IV of Figure 5, and Figure 5 is a horizontal sectional elevation taken on the line V—V of Figure 4.

Referring now to the characters of reference on the drawings:—1 indicates the furnace as a whole, 2 the hearth thereof, and 3 is the furnace roof. 4 is the mixing and primary combustion chamber of the furnace in which the air and gas are first mixed and begin their combustion prior to entrance into 90 the larger body of the furnace; the air ports and passages are 5, the gas ports and passages are 6, and 7 is the air regenerator or slag pocket or flue leading thereto. 8 is the gas regenerator or slag pocket or flue 95 leading to the gas regenerator. I also provide boxes 9 and 10 at the ends and sides of the ends of the furnace, which are made of metal and hollow and provided with water supply pipes (not shown) for the purpose 100 of supplying cooling fluid in order to protect the ends of the furnace walls from fusion or destruction from the heat. I provide deflector valves 11, the body portion 12 of which may be in the form of a hollow 105 box, which may be water cooled, the water supply and outlet thereto being carried through the hollow stem 16 in any customary manner (not shown). I may also provide an arch of refractory material or brick 13 110 on the underside of the deflector valve and a similar arch or layer of refractory material

on top of the deflector valve 14 to protect it.

As illustrated in Figure 2 of the drawings, 15 is the space between the lower side of the deflector valve 11 and the ports 5 and 6 of the furnace, and this space may be regulated by raising or lowering the deflector valve by means of the stem 16, which projects outwardly of the furnace and may be connected to any means for raising, lowering and holding the same. In case the deflector plates are long I may provide two stems as illustrated in Figure 1 of the drawings.

In Figures 1, 2 and 3 I only show one deflector valve 11, which controls the gas port 15 and which extends over the ends of the two air ports as illustrated, while in Figures 4 and 5 I provide a separate gas deflector valve 17 and two separate air deflector valves 20 over the air ports. The space between 20 the gas deflector valve 17 and the gas port is indicated as 18, and the space between the air deflector valves 20 and the air port is represented as 21. I also provide the deflector valve 17 with the stems 19, each of 25 which may be lifted or lowered, and by means of which water is supplied to and delivered from the water-cooled body of the deflector valve. The air deflector valves 20 are also provided with similar stems 22.

30 It will be noted from the construction of Figures 4 and 5 that the gas and air entrance passages 18 and 21 may be independently regulated in order to provide the best mixture, proportions and speed for combustion.

When gases are issuing into the furnace through the ports and past the deflector valves as illustrated, these deflector plates may be raised or lowered to provide the 40 best mixture, while the corresponding valves at the other end of the furnace are raised up to or near the roof of the furnace so as to provide free outlet of the products of combustion and to protect the valves from 45 the outgoing heat.

By means of my arrangement the flow of gases through the furnace is more rapid than heretofore customary, and at the same time the mixture of incoming air and gas is so 50 thorough that complete and quick combustion or combustion of the same is effected and with this speed produces a quick-working furnace.

In my invention the sizes of the entrance 55 openings through which the air and gas enter the furnace may be regulated by moving the deflector valves either closer or farther away from the openings to provide the best and most economical mixture for combustion, and to regulate the quantities of each as they are introduced, and at the same time the deflector valves at the other end of the furnace may be raised to any extent desired to provide quick exit for the products of combustion, thereby permitting a

large amount of hot burning gases to pass through in quick time, which conduces to the speed of operation. My deflector valves are also so arranged that they may practically close the port openings if desired.

70

By means of my arrangement the excess of air ordinarily introduced for the complete combustion of the gases can be reduced in quantity, thus providing an increased heat efficiency. Another advantage of my construction is that the arrangement of the deflector valves is at the ends of the furnace, thereby not encroaching on the hearth, which thereby provides a maximum length of combustion chamber allowing complete 75 combustion of gases and delivery of heat therefrom to the charge on which they operate.

80

Although I have shown and described my invention in considerable detail, I do not 85 wish to be limited to the exact and specific details thereof, as shown and described, but may use such modifications in, substitutions for, or equivalents thereof as are embraced within the scope of my invention, or as 90 pointed out in the claims.

Having thus described my invention, what I claim and desire to secure by Letters Patents is:—

1. In a reversing furnace provided with 95 gas and air ports at each end thereof, deflectors arranged adjacent to the mouths of said ports and provided with means for adjusting their position with respect to said openings.

100

2. A reversing furnace provided with gas and air ports at each end thereof, deflectors adjacent to the port openings, and provided with means for raising, lowering and holding the same in a predetermined relation to 105 the port openings.

3. A reversing gas-fired furnace provided with upwardly opening air and gas ports at each end thereof, deflectors arranged above the openings of said ports, and means for 110 raising, lowering and holding said deflectors in position.

4. In a reversing furnace, provided with air and gas ports debouching in an upward manner into the combustion chambers at 115 the ends of the furnace, water-cooled deflector valves arranged over the port openings, and provided with means for adjusting their positions with respect to the port openings.

5. In a reversing furnace, provided with 120 air and gas ports arranged respectively to discharge air and gas upwardly into a chamber in the furnace end, of means including a deflector within said chamber for deflecting an upwardly directed stream, said deflector 125 being horizontally disposed and adjustably supported by means extending downwardly through an aperture in the furnace roof.

6. In a reversing furnace, provided with air and gas ports disposed, respectively, to 130

discharge air and gas upwardly into a chamber in the furnace end, of means including a deflector within said chamber for deflecting an upwardly directed stream from a vertical, into a substantially horizontal, direction, said deflector comprising a horizontally disposed water cooled member the lower surface of which is arched in a vertical plane and which is provided with downwardly projecting abutments adjacent the margins of said arched surface whereby a protective coating of refractory brick may be retained below said surface. 10

In witness whereof I hereunto affix my signature.

MOSES APPEL.
